UNITED STATES PATENT OFFICE.

JEHIEL F. WYNKOOP, OF PHILADELPHIA, PENNSYLVANIA.

DUST-PAN.

SPECIFICATION forming part of Letters Patent No. 325,304, dated September 1, 1885.

Application filed October 10, 1884. (No model.)

To all whom it may concern:

Be it known that I, JEHIEL F. WYNKOOP, of Philadelphia, county of Philadelphia, State of Pennsylvania, have invented an Improvement in Dust-Pans, of which the following description, in connection with the accompanying drawings, is a specification, like letters on the drawings representing like parts.

My invention relates to dust-pans, and has 10 for its object to produce a more convenient dust-pan than those heretofore in use, and also one of simpler and cheaper construction, a comparatively small amount of material being required and a very small amount 15 of work needed for making the dust-pan.

The body portion of the pan is composed of a rectangular piece of sheet metal—usually tinned iron—having two of its adjacent corners folding toward one another and united 20 by a seam, thus forming a hood or shield over the bottom of the pan, which is substantially triangular in shape, one side of the said triangle forming a sweeping face or edge, over which the dirt is swept into the covered 25 receptacle, the said edge being corrugated, as hereinafter described, in order to stiffen it, and also to form a ledge to prevent the accidental discharge of dirt from the dust-pan.

30 The dust-pan is provided with a handle, preferably tubular, and united with the body of the dust-pan at the apex of the triangular dust-receptacle, the said handle being used, if desired, as a discharge-passage for the dirt collected in the dust-pan.

35 Figure 1 is a side elevation or end view of a dust-pan embodying this invention. Fig. 2 is a plan view thereof, and Fig. 3 a diagram showing the shape of the blank forming the 40 main portion or body of the pan.

The main portion *a* of the pan is made of a single rectangular piece of sheet metal, as shown in Fig. 3, having a recess, *b*, in one edge to receive the handle *c*, the corners of 45 said blank at either side of the recess *b* being folded toward one another, and the edges 23 and 45 united in a seam at *d*, (see Fig. 2,) thus forming a hood or cover over the bottom of the pan, making a dirt-receptacle 50 which confines the dust and dirt as it is swept into the pan over the edge *e* thereof.

The side of the rectangular blank that is to form the sweeping-face is corrugated or bent

upward, as shown at *f*, Fig. 1, from the level of the bottom *a* of the pan, and then inclines 55 downward, forming a sweeping-face, *e*, which extends to the floor or carpet, coming in close engagement therewith, so that the dirt will readily pass upward over the said edge into the dirt-receptacle, instead of passing beneath 60 the edge, as frequently happens with ordinary dust-pans when the edge becomes somewhat curved or warped.

The ridge at *f* prevents the dirt from easily escaping from the dust-receptacle after it has 65 been swept up over the face *e*.

The dust-pan made of a rectangular blank, as described, has as long a sweeping edge or face as the usual dust-pans made of a blank of equal size, and the triangular hooded receptacle receives and confines the dirt better 70 than an open pan.

The handle *c* is connected with the pan at the apex of the triangle, a band, *h*, being preferably employed to strengthen the joint 75 between the said handle and body of the pan. The handle is shown as tubular, and is preferably left open, thus forming a discharge-passage from the apex of the triangle, which may be used to empty the dirt, if desired, or 80 the dirt may be discharged from the hood at either end of the sweeping-edge *e*.

It is obvious that a pan of this construction is well adapted for a crumb-tray for table use. Any suitable form of handle may be employed. 85

I am aware that a covered dust-pan has been made from a single blank, adjacent edges of which were seamed together; also, that a dust-pan has been provided with a corrugated 90 sweeping-face; but such construction I do not herein broadly claim.

I claim—

A dust-pan having a triangular covered dirt-receptacle, and an open tubular handle 95 connected therewith at the apex of the triangle, and adapted to serve as a discharge-passage, substantially as described.

In testimony whereof I have signed my name to this specification in the presence of two sub- 100 scribing witnesses.

JEHIEL F. WYNKOOP.
